16 Claims. (Cl. 196—37)

This invention relates to an improved method for the treatment of liquid hydrocarbons, particularly mineral oils, with liquid-SO₂ and like solvents used over and over, that is, maintained in 5 a closed cycle.

More specifically, the invention in its broad aspect relates to the use of automatic control means for cyclical systems providing for sufficient flexibility of operation that without manual 10 regulation, the finished products freed of solvent can be continuously secured from various petroleum fractions continuously introduced and treated with varying amounts of solvent.

The invention has special reference to the well 15 known "Edeleanu process" of treating petroleum fractions. Briefly, this process consists in mixing the oil or fraction with liquid-SO₂, the latter being a solvent for unsaturated, aromatic, sulfur containing, and carbon-residue producing constituents, and being relatively insoluble in the 20 saturated constituents. Upon allowing equilibrium to be reached, the mixture separates into two phases, or layers, the upper being known as the "raffinate" layer and the lower as the "extract" layer. The upper layer consists of the refined oil ("raffinate") containing a small 25 amount of dissolved liquid-SO₂, and will be referred to hereafter as the "raffinate-solution". The lower layer consists of the bulk of the liquid- 30 SO₂ containing the extracted compounds (which have value as by-products), and will be referred to hereafter as the "extract-solution". The two layers are mechanically separated and freed of liquid-SO₂, resulting in the finished "raffinate" 35 and finished "extract".

In actual practice, a continuous, closed treatment cycle is used and the liquid-SO₂ recovered and reused. The untreated oil is continuously introduced and treated with the liquid-SO₂ in a 40 counter-current tower, the raffinate-solution being continuously withdrawn from the upper part of the tower and the extract-solution from the lower part. The respective solutions are freed from the contained liquid-SO₂ by being passed 45 through a series of evaporators, the first stage in each case being under pressure and the last stage under vacuum, whereby the liquid-SO₂ is driven off as a vapor. The liquid-SO₂ vapor is collected, condensed, and reused.

50 The patent to Cattaneo, Edeleanu, et al., No. 1,840,765, issued January 12, 1932, may be referred to for further details of the Edeleanu "continuous treatment" process as heretofore practised in the United States and many foreign 55 countries.

In some cases a continuous multiple-batch method of treatment is used wherein the untreated oil is not treated in a counter-current tower but in a series of mixing tanks and settling tanks, as illustrated in the patent to Edeleanu et al., No. 1,666,560, issued April 17, 1928. In this case, the raffinate-solution and extract-solution are likewise free of liquid-SO₂ in a series of evaporators and the recovered liquid-SO₂ reused. In either method of treatment, the extraction or treatment apparatus is referred to as the "mixer".

With respect to the extraction- or treatment part of the systems heretofore used, it has been necessary to provide a collecting tank for the raffinate-solution leaving the mixer and a corresponding collecting tank for the extract-solution, in order that a steady flow of the solutions to the evaporation (liquid-SO₂ recovery) part of the system would be maintained in case the mixing process became temporarily disturbed, as 75 would be the case when a fluctuation occurred in the flow of untreated oil or liquid-SO₂ admitted to the mixer. Furthermore, it has been necessary to provide a great number of sight-glasses in the mixer in order to control that the upper 80 level (top of raffinate-solution) would not fall below the upper outlet, as this would cause the raffinate-solution pump to lose suction and interrupt the flow of solution to the evaporator; and so that the lower level (top of extract-solution and bottom of raffinate-solution) would be maintained at a mid-point to prevent extract-solution from being drawn off by the raffinate-solution pump or raffinate-solution being drawn off by the extract-solution pump.

It has been found that the expensive collecting tanks and the operators supervising them may be dispensed with and a more effective automatic control secured. This is accomplished, in the case where a counter-current tower is used as the mixer, by passing a portion of the raffinate-solution drawn from the tower back into the upper part of the tower, the amount thus returned being regulated by a float controlled valve responsive to fluctuations in the upper level; and by also passing a portion of the extract-solution back into the lower part of the tower, the amount so returned being regulated by a float controlled valve responsive to fluctuations in the lower level. This recirculation is effected by the respective 95 raffinate-solution and extract-solution pumps, which must of course have a sufficient capacity to take care of both the direct flow to the evaporators and the recirculating flow.

When a series of mixing and settling tanks are 100 110

used in place of a counter-current tower, the desired result is secured by equipping the first and last settling tanks with level controls, operated in the same way as those of the counter-current tower. In some cases it may be desirable to equip all of the settling tanks with level controls.

In both instances, the improved result may be broadly characterized as following from automatic maintenance of the levels in the "mixer" (treating and separating apparatus).

With respect to the evaporation (liquid-SO₂ recovery) part of the system, it has heretofore been necessary to provide very voluminous evaporator drums in which the fluctuations in the flow of the solutions were equalized before entering the more sensitive vacuum evaporators where such fluctuations would otherwise cause an undesirable increase in the final SO₂ content of the finished raffinate and extract.

The low pressure and vacuum evaporators have a limited operating capacity, as it is necessary to provide gas pumps for drawing off the expelled SO₂ vapors and compressing them up to a pressure such that condensation can be effected with cooling water, and these gas pumps necessarily have a limited suction capacity. In case that the premise stages of the evaporation systems were not carefully supervised and the supply of heat to these evaporators was not constantly accommodated to the fluctuations in the flow of the solutions, it was unavoidable that with a small increase in the liquid-SO₂ concentration in the solutions entering the vacuum evaporators, the gas pumps would not be able to completely remove the evolved SO₂ and hence a pressure would build up which would prevent the evolution of sufficient SO₂ necessary for the production of a pure raffinate and extract.

It has been found possible by a particular combination of pressure and temperature controls on the pressure evaporators (which do not require gas pumps) and of level controls regulating the liquid levels in the evaporators and the flow of solution therebetween, to permit of small capacity evaporators and the securing of the desired SO₂-free raffinate and extract despite fluctuations in the incoming raffinate and extract solutions, whether due to changes in the oil being treated, changes in the amount of liquid-SO₂ used for treatment, or other changes.

The result of these improvements in both the extraction and evaporation parts of the system is that the cost of the plant, the operating expenses, and number of operators are all materially reduced and a more uniform and satisfactory continuous operation under varying conditions is effected, whereby a more uniform refined product will be produced. Various specific advantages will be evident to those skilled in the art from the following detailed description.

In the accompanying drawings, wherein I have shown one embodiment of my invention for purposes of illustration,

Fig. 1 is a flow sheet of a complete extraction and liquid-SO₂ recovery system for the continuous refining of mineral oils with liquid-SO₂;

Fig. 2 is a vertical central section, partly diagrammatic, of a portion of the mixer and the level control for the raffinate-solution in the mixer, indicated diagrammatically in Fig. 1; and

Fig. 3 is a vertical central section, partly diagrammatic, of a fluid level control for the evaporators, indicated diagrammatically in Fig. 1.

Referring to Fig. 1, the untreated petroleum

fraction or oil is pumped by liquid transfer pump 10 through line 11 into the lower part of the counter-current tower or mixer 12, being directed upwardly therein. Liquid-SO₂ in tank 13 is cooled down to the required extraction treatment temperature (as hereafter described) and pumped by liquid transfer pump 14 through line 15 into the upper part of the mixer 12, being directed downwardly therein.

Due to the specific gravity of the liquid-SO₂ being greater than that of the oil, the two will pass in counter-current relation to each other within the mixer, the oil rising and the liquid-SO₂ sinking. As the oil rises, the constituents that it is desired to remove will be extracted by the liquid-SO₂ and the resulting raffinate-solution, containing usually about 10-20% by weight of liquid-SO₂ dissolved therein, will collect in the upper part of the mixer. The liquid-SO₂ and constituents dissolved therein (which are, in general, the unsaturated, aromatic compounds comprised in the oil) i. e., the resulting extract-solution containing usually 80-90% of liquid-SO₂, collects in the bottom part of the mixer 12.

Due to the double phase effect, previously described, the result will be an upper layer of raffinate-solution resting on a lower layer of extract-solution. Two levels will exist, the upper level being the top of the raffinate-solution layer; and the lower level being the top of the extract-solution layer, this being also the plane of demarcation between the two layers.

The raffinate-solution is withdrawn from the mixer 12, at a point above the liquid-SO₂ inlet, through line 16 by liquid transfer pump 17 and into line 18, controlled by valve 19.

The upper level of the raffinate-solution in the mixer 12 is maintained at the desired point above the outlet by forcing a portion of the raffinate-solution in line 18 back into the upper part of mixer 12, this being accomplished by pump 17 and line 20 which branches off from line 18 in advance of valve 19. The amount of raffinate-solution thus circulated back is regulated by float controlled valve 21 which is responsive to changes in the upper level and automatically admits to the mixer 12 the proper amount of recirculated raffinate-solution to maintain the level at the predetermined point.

An illustrative form of valve 21 is shown in detail in Fig. 2. Referring to Fig. 2, the outlet 22 in the upper part of mixer 12 conducts the raffinate-solution into line 16. The raffinate-solution circulated back flows through line 20 to valve 21, which has a regulating chamber 23 communicating with line 20 and with line 24, the latter conducting the recirculated raffinate-solution into the upper part of the mixer at a point below outlet 22.

Valve 21 has a float chamber 25 above the regulating chamber. The float chamber communicates with mixer 12 by means of two pipes: pipe 26 which enters the mixer at a point just above the desired raffinate-solution (upper) level, and pipe 27 which enters just below this level.

Within chamber 25 is a float 28 which is attached by dependent vertical rod 29 to the valve mechanism in chamber 23. The two chambers are separated by wall 30, the latter having a sleeve 31 through which passes rod 29.

With this arrangement it is evident that the raffinate-solution from the mixer can flow freely into chamber 25 and that the liquid level in this chamber will at all times be the same as that in the mixer. Float 28 and rod 29 will therefore

rise or fall in exact correspondence with a rise or fall of the upper level in the mixer.

Line 20 communicates with valve chamber 32 (contained within regulating chamber 23) and this chamber has two vertical conical extensions 5 concentric with rod 29, and communicating with chamber 23. The upper conical extension narrows upwardly and the lower conical extension widens downwardly. Attached to rod 29 are two 10 valve disks, 33 and 34, contained respectively within the upper and lower conical extensions of chamber 32.

It will be seen that an upward movement of rod 29 (and valve disks 33 and 34) will cause an increased resistance to the flow of raffinate-solution 15 from line 20 to pipe 24 and the mixer, and visa versa, with the result that the rate of flow of raffinate-solution back into the mixer will increase when the upper level drops and will decrease when the upper level rises.

Thus valve 21, by automatically increasing or decreasing the amount of raffinate-solution forced back into the mixer through line 20 by pump 17, causes the upper level in the mixer to be maintained at a predetermined point above the 25 raffinate-solution outlet.

Referring again to Fig. 1, the extract-solution is drawn from the bottom of mixer 12 into line 35, by liquid transfer pump 36, and is forced into line 37, controlled by valve 38. A portion of the extract-solution is continuously recirculated back into the lower part of the mixer, passing through line 39 which branches off from line 37 at a point in advance of valve 38. Pump 36 serves to force 30 the recirculated solution through line 39 and the rate of flow is automatically regulated by float controlled valve 40, which is responsive to changes in the lower level (top of extract-solution) in the mixer. Valve 40 is similar to valve 21 already 40 described and shown in Fig. 2, and the arrangement results in the lower level in the mixer being automatically maintained at a predetermined point between the bottom outlet and the top outlet.

The foregoing description relates to the extraction part of the system. The following description relates to the evaporation part of the system, wherein the raffinate-solution and extract-solution are freed of liquid-SO₂ and the latter recovered.

The extract-solution is carried by line 37 through heat-exchanger 50, where it is heated by the finished extract leaving the system, and then passes through heating device 51 and into "high-pressure evaporator" 52 which in the illustrative apparatus consists of a vertical drum.

This high-pressure evaporator is provided in the extract evaporation system only for the purpose of recovering by multiple effect a part of the heat necessary for the evaporation of the large amount of SO₂ in the extract solution. This multiple effect is achieved in such a way that SO₂ vapors expelled from the extract-solution at high pressure are used as heating medium in the next following pressure stage.

High-pressure evaporator 52 is operated at a pressure of about 11-13 atm. abs. (150-180 pounds gauge). It has been found that the concentration of the extract-solution leaving the evaporator drum can be maintained substantially constant (this being an important part of the invention) by adjusting the temperature of the incoming extract-solution so as to maintain a substantially constant pressure in the evaporator drum. The temperature control of the extract-

solution entering high-pressure evaporator 52 is effected by regulating the amount of heat added to the solution in heating device 51 by means responsive to changes in pressure in evaporator 52.

The heating is effected by steam which enters by line 53 and flows partly through line 54 (controlled by valve 55) and partly through by-pass line 56 (controlled by valve 57) to line 58, and thence through heating device 51, from which it leaves by line 59. Valve 55 is automatically controlled by pressure responsive device 60 which responds to changes in the vapor pressure in evaporator 52 and increases the flow of steam in line 54 when the pressure falls in the evaporator and decreases the flow of steam when the pressure rises therein.

It has been found that the concentration of the extract-solution leaving the high pressure evaporator can be maintained more nearly uniform in this way than if the heating is controlled by means responsive to changes in temperature in the evaporator, as it has been found that variations in the liquid-SO₂ content of the solution in the high-pressure evaporator produce greater relative changes in pressure than relative changes in temperature.

The liquid level in high-pressure evaporator 52 is maintained constant by float controlled valve 61 which regulates the flow of extract-solution leaving the evaporator by line 62, this valve also serving to reduce the pressure in line 62 to that of the next and lower pressure evaporator.

Referring to Fig. 3, which shows valve 61 in detail, it will be seen that this valve is somewhat similar to valve 21, shown in Fig. 2 and described in connection therewith, with the difference that the flow through valve 61 is decreased rather than increased by a fall in the liquid level actuating the valve float.

The high-pressure evaporator 52 communicates with float chamber 63 of valve 61 by means of pipe 64 which is positioned just above the liquid level, and pipe 65 which enters the evaporator drum below the liquid level, these two connections causing a liquid level to be maintained in float chamber 63 corresponding to that in the evaporator. Float 66 and vertical rod 67 depending therefrom into regulating chamber 68 of the valve rise or fall in direct response to a rise or fall of the liquid level.

Line 62, coming from the bottom of the high-pressure evaporator, communicates with regulating chamber 68 of the valve. Within regulating chamber 68 is a valve chamber 69, communicating directly with outlet line 70 of the valve, and having two vertical conical extensions concentric with rod 67 and communicating with chamber 68. The upper conical extension widens upwardly and the lower conical extension narrows downwardly. Attached to rod 67 are two valve disks 71 and 72, contained respectively within the upper and lower conical extensions of chamber 69.

It will be seen that an upward movement of rod 67 (and valve disks 71 and 72), corresponding to a rise in the liquid level in evaporator 52, will cause a decreased resistance to the flow of extract-solution from evaporator 52, and hence will bring about a lowering of the liquid level in evaporator 52, and visa versa. This valve thus regulates the flow of extract-solution from high-pressure evaporator 52 so as to maintain a constant liquid level in the latter.

Referring again to Fig. 1, the SO₂ vapor evolved

in high-pressure evaporator 52 is withdrawn from the top of the evaporator by line 73 and passes through heat-exchanger 75 where it is condensed as the result of being cooled by cooler extract-solution from the high-pressure evaporator 52, which is cooled by the vaporization of part of the SO₂ contained therein caused by the reduction in its pressure occurring at the control valve 61.

The condensed SO₂ vapor from heat exchanger 75 flows through line 73 to valve 76, where its pressure is reduced to condenser pressure and thence by line 77, controlled by valve 78, to liquid-SO₂ storage tank 13.

The extract-solution is continuously withdrawn from evaporator 52 by line 62, controlled by valve 61, just described, and flows by line 70 through heat exchanger 75, where it becomes heated by condensing of the hot SO₂ vapor passing through the heat exchanger by line 73.

The extract-solution leaving heat exchanger 75, having now had a large portion of its SO₂ content removed, is further evaporated at "condenser-pressure"—this pressure (normally 4-6 atm. abs.) being such that the evolved SO₂ vapors can be condensed in a water cooled condenser. The condenser-pressure evaporation is effected in two stages, consisting of vapor chamber 79 and the evaporator 80.

The extract-solution, having been heated in heat exchanger 75, enters the upper part of vapor chamber 79 which is maintained at condenser-pressure by having its upper part connected by line 81 to the upper part of condenser-pressure evaporator 80. Additional evaporation of SO₂ from the extract-solution takes place in chamber 79 since the solution is not only at a higher temperature but at a lower pressure than when it left high-pressure evaporator 52. The evolved SO₂ vapor passes by line 81 into the upper part of condenser-pressure evaporator 80; while the depleted extract-solution is withdrawn from the bottom of evaporation chamber 79 by line 82, and flows through steam heater 83 and thence into condenser-pressure evaporator 80. Heating is effected by steam entering by line 84, the amount being automatically regulated by valve 85 in a manner similar to the steam regulation of heater 51 already described, and after flowing through heater 83 it leaves by line 86.

Valve 85 is automatically controlled by a temperature responsive device 87 which responds to changes in the temperature of the liquid in condenser-pressure evaporator 80, and thus controls the heating of the extract-solution entering the evaporator so that the liquid in the evaporator will be maintained at constant temperature.

It has been found that the liquid-SO₂ concentration in the extract-solution leaving the condenser-pressure evaporator 80 can be maintained constant (which is an important part of our invention) by thus maintaining the temperature of the liquid in the evaporator. It has also been found that a change in concentration is reflected in this case by a greater relative change in temperature than relative change in pressure, and hence that it is advantageous to have the flow of steam in heater 83 controlled by means responsive to temperature changes in the liquid in the evaporator. This means of control is just the opposite to what has been found most desirable with respect to the heating control of the extract-solution entering the high-pressure evaporator.

In condenser-pressure evaporator 80, a further evaporation of SO₂ from the extract-solution

occurs due to the heating to which the latter has been subjected since leaving vapor chamber 79.

The evolved SO₂ vapor, together with the SO₂ vapor from vapor chamber 79, leaves the top of condenser-pressure evaporator 80 by line 88 and thence passes to line 89, leading to condenser 90, where the SO₂ vapor is condensed by cooling water.

The depleted extract-solution leaves the bottom of condenser-pressure evaporator 80 by line 91, the rate of flow being controlled by float controlled valve 92 so as to maintain a constant liquid level in the evaporator. Valve 92 and the means of control is identical with valve 61 already described and shown in detail in Fig. 3.

The extract-solution passes through steam heater 93 and into atmospheric-pressure evaporator 95, which is maintained at a pressure of about 3 1/4 atm. abs. Due to the reduction in pressure and the heating, a further amount of SO₂ will be expelled from the solution and the evolved SO₂ vapor is withdrawn from the top of the evaporator 95 through line 96 which connects with line 97 leading to the low pressure side of gas pump 98, and this pump serves to withdraw the SO₂ vapor from evaporator 95 and to maintain the desired pressure therein.

Due to the arrangement described, pump 98 need not be designed to care for possible high over loads, since the extract-solution entering atmospheric-pressure evaporator 95 will have a substantially constant SO₂ concentration, and this will prevent large fluctuations in the amount of SO₂ vapor evolved in the evaporator.

The depleted extract-solution leaves the bottom of atmospheric-pressure evaporator 95 by line 99, the rate of egress being controlled by valve 100 (which may be identical with valves 61 and 92) so as to maintain a constant liquid level in the evaporator. From valve 100 the extract-solution flows with or without further heating to vacuum evaporator 101 in which a high vacuum is maintained. Due to the latter, a practically complete removal of SO₂ from the extract-solution may be effected. The SO₂ vapor evolved in evaporator 101 is withdrawn from the top through line 102, which communicates with line 103 leading to the low pressure side of gas pump 104 which serves to maintain the high vacuum in the evaporator.

This pump 104 also need not be designed for large over loads, as the amount of SO₂ vapor evolved in vacuum evaporator 101 will not vary much, due to the substantially constant SO₂ concentration of the incoming extract-solution resulting from the control arrangement described.

Furthermore, due to the substantially constant SO₂ concentration of the incoming extract-solution, there will be no danger that insufficient SO₂ will be evolved from the solution during its passage through the evaporator to cause the extract leaving the evaporator to have too high an SO₂ content.

The liquid leaves the bottom of vacuum evaporator 101 through line 105, as finished "extract" practically freed of liquid-SO₂. Liquid transfer pump 106 forces the extract into line 110, controlled by valve 107, through which it leaves the system, after first passing through heat exchanger 145 50 in which it is cooled.

The liquid level in vacuum evaporator 101 is maintained constant in the same way as the upper level in the mixer 12 is maintained constant. A portion of the extract is recirculated through line 150

108, which branches off from line 110 between the pump and the valve, back to line 105 which leads from the bottom of the evaporator to the pump 106. The rate of recirculation is regulated by 5 float controlled valve 109 which is responsive to changes in the liquid level in the evaporator and which has the same construction as valve 21, shown in Fig. 2, already described. Pump 106 runs at a constant rate and hence the effect 10 of recirculating a portion of the extract is to raise or lower the liquid level in the evaporator as the rate of recirculation is increased or diminished by valve 109. Thus the liquid level is held constant.

15 Having now described the removal of the liquid-SO₂ from the extract-solution, the removal of the liquid-SO₂ from the raffinate-solution leaving mixer 12 will now be described. This removal is effected in condenser-pressure evaporator 122, atmospheric-pressure evaporator 128, and vacuum evaporator 132, which correspond respectively to extract-solution evaporators 80, 95 and 101, and which have corresponding automatic control devices, and hence need not be described in detail.

20 The raffinate-solution from mixer 12 flows through line 18 and passes through heat exchanger 120 where it is heated by the finished raffinate leaving the system. The raffinate-solution then passes through heater 121 and into condenser-pressure evaporator 122. The amount of steam passing through heater 121 is automatically regulated by temperature responsive device 123 (corresponding to temperature responsive device 87 already described) so that the temperature of the liquid in the evaporator 122 will be held constant, and hence the SO₂ concentration in the raffinate-solution leaving the evaporator will be maintained substantially constant.

25 The evolved SO₂ vapor passes into line 124 and is conducted to line 88 and thence to the condenser 90.

30 The depleted raffinate-solution leaves the condenser-pressure evaporator 122 by line 125, the flow being regulated by valve 126 (corresponding to valve 92) so as to maintain a constant liquid level in the evaporator, and passes through heater 127 and into atmospheric-pressure evaporator 128.

35 Pump 98 serves to withdraw from this evaporator 128 the SO₂ vapors evolved therein which leave it by line 129 and pass through line 97 leading to the low pressure side of the pump.

40 The depleted raffinate-solution leaves the bottom of atmospheric-pressure evaporator 128 by line 130, controlled by valve 131 (corresponding to valve 100) so as to automatically maintain the liquid level in the evaporator, and flows directly into vacuum evaporator 132. There the final amount of SO₂ evaporates off, due to the high 45 vacuum, and is withdrawn through line 133 and the communicating line 103 leading to the low pressure side of gas pump 104.

45 The finished "raffinate" is withdrawn from the vacuum evaporator 132 through line 134 by liquid transfer pump 135, and is forced into line 136, controlled by valve 137, through which, after passing through heat exchanger 120, it leaves the system.

50 As with extract vacuum evaporator 101, the liquid level is automatically maintained constant in raffinate vacuum evaporator 132 by recirculating a portion of the raffinate, the rate of flow being regulated by float controlled valve 138 (corresponding to valve 109).

55 The SO₂ vapors from the extract-solution and

raffinate-solution vacuum evaporators (101, 132) enter pump 104 by line 103 and are pumped up to atmospheric pressure and forced through line 140 into line 97 where they join the SO₂ vapors from the two atmospheric-pressure evaporators (95, 128). The combined SO₂ vapors in line 97 are compressed to condenser-pressure and forced by pump 98 into line 89. Here they commingle with the SO₂ vapors from the two condenser-pressure evaporators (80, 122) which enter by line 88 into line 89.

60 Line 89 leads to condenser 90 to which are conducted the SO₂ vapors from all of the evaporators, excepting those from extract high-pressure evaporator 52. Condenser 90 is of suitable design and capacity, and condenses these SO₂ vapors at the pressure corresponding to the temperature of the cooling water. The liquid-SO₂ so obtained is led from the condenser by line 141 to storage tank 142.

65 From tank 142 the liquid-SO₂ flows into line 77 where it joins the liquid-SO₂ coming by line 73 from extract high-pressure evaporator 52 and having been condensed in heat exchanger 75. The combined liquid-SO₂ in line 77, which represents all of the liquid-SO₂ recovered from both the raffinate and extract solutions, flows into tank 13 through pressure reduction valve 78.

70 In tank 13 the liquid-SO₂ is cooled down to the temperature desired for treatment of the mineral oil in mixer 12. Cooling may be effected by external means or may be accomplished directly by evaporation of a portion of the liquid-SO₂ in the tank. This latter method is illustrated in Fig. 1. Line 143 leads from the top of tank 13 to line 97 which is connected to the low pressure side of pump 98. Valve 144 in line 143 may be adjusted so as to permit of the desired amount of evaporation in tank 13 and in this way the liquid-SO₂ may be cooled as desired before being pumped into mixer 12.

75 In some cases it may be necessary only to provide the first and final evaporators of the respective raffinate and extract evaporators with automatic valves for controlling the constant level and outflow of the liquid therein. In other cases the above described extract-high pressure evaporator may be dispensed with and the extract solution directly passed into the condenser pressure evaporator. The steam supply to this evaporator would also in this case be regulated by temperature control.

80 While the detailed description of the system has been with respect to the treatment of mineral oils and like liquid hydrocarbons with liquid-SO₂, it will be obvious to those skilled in the art that the invention is applicable to treatment with the recovery of other solvents than liquid-SO₂; and is applicable to the use and recovery of mixed-solvents containing liquid-SO₂, such as liquid-SO₂-benzol mixtures. Furthermore, the invention is obviously not restricted to the particular embodiment thereof herein illustrated and described.

85 The term "volatile solvents" is used in the claims to denote solvents removable by evaporation from the extract and raffinate of the mineral oil treated, i. e., solvents having boiling points low enough to permit of recovery in evaporation systems of the class herein described. This term is not used restrictively to include use of only one solvent, but applies also to mixtures of solvents containing at least one volatile solvent of the character indicated, as for example, a mixture of liquid-SO₂ and benzol.

Having described one illustrative embodiment of the invention, what is claimed is as follows:

1. An improvement in the method of continuously refining mineral oils with volatile solvents such as liquid-SO₂ and the like, said method including the steps of treating the oil with the solvent, separating out the resulting raffinate-solution and extract-solution and subjecting the same to evaporation for removal of the solvent for reuse; the raffinate solution being evaporated successively in zones operated under condenser-pressure, atmospheric-pressure and under high vacuum, and the extract-solution being evaporated successively in zones operated under high-pressure, condenser-pressure, atmospheric-pressure and under high vacuum; which improvement comprises automatically maintaining the liquid levels constant at predetermined points in the treatment and evaporation zones, 5 automatically maintaining a constant predetermined pressure in the extract high-pressure evaporation zone by controlling the heating of the extract-solution entering said zone by and in response to changes of pressure in said zone, 10 and automatically maintaining a constant predetermined temperature in the respective raffinate and extract condenser-pressure evaporation zones by controlling the heating of the solutions entering said zones by and in response to changes 15 of temperature in said zones.
2. An improvement in the method of continuously refining mineral oils with volatile solvents such as liquid-SO₂ and the like, said method including the steps of treating the oil with the solvent, separating out the resulting raffinate-solution and extract-solution and subjecting the same to evaporation for removal of the solvent for reuse; the raffinate-solution being evaporated successively in zones operated under condenser-pressure, atmospheric-pressure and under high 20 vacuum, and the extract-solution being evaporated successively in zones operated under high-pressure, condenser-pressure, atmospheric-pressure and under high vacuum; which improvement comprises maintaining the liquid levels constant at predetermined points in the various evaporation zones by controlling the rate of out-flow of liquid therefrom by and in response to changes 25 in said levels in the case of all except the vacuum evaporators, and in the case of the vacuum evaporation zones maintaining the liquid levels constant at predetermined points by continuously recirculating thereto a portion of the respective finished raffinate and extract at a rate controlled 30 by and in response to changes in level therein.
3. An improvement in the method of continuously refining mineral oils with volatile solvents such as liquid-SO₂ and the like, said method including the steps of treating the oil with the solvent, separating out the resulting raffinate-solution and extract-solution and subjecting the same to evaporation for removal of the solvent for reuse; the raffinate-solution being evaporated successively in zones operated under condenser-pressure, atmospheric-pressure and under high 35 vacuum, and the extract-solution being evaporated successively in zones operated under high-pressure, condenser-pressure, atmospheric-pressure and under high vacuum; which improvement comprises automatically maintaining the liquid levels constant at predetermined points in the evaporation zones, automatically maintaining a constant predetermined pressure in the extract high-pressure evaporation zone by controlling the heating of the extract-solution entering said zone by and in response to changes of pressure therein, and automatically maintaining a constant predetermined temperature in the respective raffinate and extract condenser-pressure evaporation zones by controlling the heating of the incoming solutions entering said zones by and in response to changes of temperature therein.
4. An improvement in the method of continuously refining mineral oils with volatile solvents such as liquid-SO₂ and the like, said method including the steps of treating the oil with the solvent, separating out the resulting raffinate-solution and extract-solution and subjecting the same to evaporation for removal of the solvent for reuse; the raffinate-solution being evaporated successively in zones operated under condenser-pressure, atmospheric-pressure and under high 40 vacuum, and the extract-solution being evaporated successively in zones operated under high-pressure, condenser-pressure, atmospheric-pressure and under high vacuum; which improvement comprises maintaining the liquid levels constant at predetermined points in the various evaporation zones by controlling the rate of out-flow of liquid therefrom by and in response to changes in said levels in the case of all except the vacuum evaporators, and in the case of the vacuum evaporation zones maintaining the liquid levels constant at predetermined points by continuously recirculating thereto a portion of the respective finished raffinate and extract at a rate controlled 45 by and in response to changes in level therein.
5. An improvement in the method of continuously refining mineral oils with solvents such as liquid-SO₂ or solvent mixtures containing SO₂, said method including the steps of treating the oil with the solvent, separating out the resulting raffinate-solution and extract-solution and removing the solvent therefrom by separately passing the respective solutions through successive evaporation zones operated at decreasing pressures, the next to last zone in each case being under atmospheric-pressure and the final zone under vacuum; which improvement comprises automatically maintaining the liquid levels constant at predetermined points in the treatment and evaporation zones, and maintaining a substantially constant predetermined solvent concentration in the raffinate and extract solutions entering the respective atmospheric-pressure evaporation zones by automatically controlling the heating of the same solutions when entering the preceding evaporation zones so as to maintain a substantially constant solvent concentration therein.
6. An improvement in the method of continuously refining mineral oils with solvents such as liquid-SO₂ or solvent mixtures containing SO₂, said method including the steps of treating the oil with the solvent, separating out the resulting raffinate-solution and extract-solution and removing the solvent therefrom by separately passing the respective solutions through successive evaporation zones operated at decreasing pressures, the next to last evaporation zone in each

- case being under atmospheric-pressure and the final evaporation zone under vacuum; which improvement comprises automatically maintaining the liquid levels constant at predetermined points in the various evaporation zones, and maintaining a substantially constant predetermined solvent concentration in the raffinate and extract solutions entering the respective atmospheric-pressure evaporation zones by automatically controlling the heating of the same solutions when entering the preceding evaporation zones so as to maintain a substantially constant solvent concentration therein.
7. An improvement in the method of continuously refining mineral oils with solvents such as liquid-SO₂ or solvent mixtures containing SO₂, said method including the steps of treating the oil with the solvent, separating out the resulting raffinate-solution and extract-solution and removing the solvent therefrom by separately passing the respective solutions through systems of successive evaporation zones operated at decreasing pressures, the next to last evaporation zone in each case being under atmospheric-pressure and the final evaporation zone under vacuum; which improvement comprises automatically maintaining the liquid levels constant at predetermined points in the first and final evaporation zones of the respective raffinate and extract evaporation systems, and maintaining a substantially constant predetermined solvent concentration in the raffinate and extract solutions entering the respective atmospheric-pressure evaporation zones by automatically controlling the heating of the same solutions when entering the preceding evaporation zones so as to maintain a substantially constant solvent concentration therein.
8. An improvement in the method of recovering the solvent contained in the extract-solution resulting from the treatment of mineral oils with volatile solvents such as liquid-SO₂ and the like, said method including the steps of passing the extract-solution through successive evaporation zones operated at decreasing orders of pressure and including a high-pressure evaporation zone; which improvement comprises maintaining a substantially constant solvent concentration of the extract-solution flowing from the high-pressure evaporation zone by automatically controlling the heating of the extract-solution entering said zone by and in response to changes in the pressure therein so as to maintain said pressure constant.
9. The method according to claim 8 in which the liquid level in the high-pressure evaporation zone is maintained at a predetermined point by automatically controlling the out-flow of the extract-solution therefrom by and in response to changes in the liquid level therein.
10. An improvement in the method of recovering the solvent contained in the extract-solution resulting from the treatment of mineral oils with volatile solvents such as liquid-SO₂ and the like, said method including the steps of passing the extract-solution through successive evaporation zones operated at decreasing orders of pressure and including a condenser-pressure zone; which improvement comprises maintaining a substantially constant solvent concentration of the extract-solution flowing from the condenser-pressure evaporation zone by automatically controlling the heating of the extract-solution entering said zone by and in response to changes in the liquid level therein so as to maintain said temperature constant.
11. The method according to claim 10 in which the liquid level in the condenser-pressure evaporation zone is maintained at a predetermined point by automatically controlling the outflow of the extract-solution therefrom by and in response to changes in the liquid level therein.
12. An improvement in the method of recovering the solvent contained in the raffinate-solution resulting from the treatment of mineral oils with volatile solvents such as liquid-SO₂ and the like, said method including the steps of passing the raffinate-solution through successive evaporation zones operated at decreasing orders of pressure and including a condenser-pressure evaporation zone; which improvement comprises maintaining a substantially constant solvent concentration of the raffinate-solution flowing from the condenser pressure evaporation zone by automatically controlling the heating of the raffinate-solution entering said zone by and in response to changes in the liquid temperature therein so as to maintain said temperature constant.
13. The method according to claim 12 in which the liquid level in the condenser-pressure evaporation zone is maintained at a predetermined point by automatically controlling the out flow of the raffinate-solution therefrom by and in response to changes in the liquid level therein.
14. An improvement in the method of recovering the solvent contained in the extract-solution resulting from the treatment of mineral oils with volatile solvents such as liquid-SO₂ and the like, said method including the steps of passing the extract-solution through successive evaporation zones operated at decreasing orders of pressure and including a high-pressure zone followed by a condenser-pressure zone; which improvement comprises maintaining a substantially constant solvent concentration of the extract-solution flowing from the high-pressure and condenser-pressure evaporation zones by automatically controlling the heating of the extract-solution entering the high-pressure zone by and in response to changes in the vapor pressure in said zone so as to maintain a constant vapor pressure therein and by automatically controlling the heating of the extract-solution entering the condenser-pressure zone by and in response to changes in the liquid temperature in said condenser-pressure zone so as to maintain a constant temperature of the extract-solution therein, and maintaining the liquid level at a predetermined point in said high-pressure zone by automatically controlling the rate of out flow of the extract solution therefrom by and in response to changes in the liquid level therein.
15. In a method of recovering the solvent contained in the extract-solution resulting from the treatment of mineral oils with volatile solvents such as liquid-SO₂ and the like, which includes passing the extract-solution through a high-pressure evaporation zone, the step of automatically controlling the heating of the solution entering said zone by and in response to changes in the pressure therein so as to maintain said pressure constant and thereby maintain a substantially constant solvent concentration in the solution leaving said zone.
16. In a method of recovering the solvent contained in raffinate and extract solutions resulting from the treatment of mineral oils with volatile solvents such as liquid-SO₂ and the like, which

includes passing the solvent-containing solution through a condenser-pressure evaporation zone, the step of automatically controlling the heating of the solution entering said zone by and in response to changes in the liquid temperature therein so as to maintain said temperature con-

stant and thereby maintain a substantially constant solvent concentration in the solution leaving said zone.
